Original design application June 11, 1936, Serial
No. 63,232. Divided and this application
August 18, 1936, Serial No. 64,460

Term of patent 14 years

To all whom it may concern:

Be it known that we, Macy H. Stein and Max S. Stein, citizens of the United States and residents of 1 Seaman Avenue, in the city, county, and State of New York, have invented a new, original, and ornamental Design for a Combination Lipstick and Holder Therefor, of which the following is a specification, reference being had to the accompanying drawing forming part thereof:

Fig. 1 is a perspective view of the article showing our new design in a closed position; and

Figs. 2 and 3 are perspective views of the same in open positions; Fig. 2 showing the lipstick element telescoped and Fig. 3 showing the same retracted.

The essential feature of our design resides in the container element and it is contemplated that the same may be used as a receptacle for other articles than that of a lipstick without departing from the spirit of the invention.

This application is a division of our copending application Serial No. Des. 63,232, filed June 11, 1936, for a watch case or similar article.

We claim:

The ornamental design for a combination lipstick and holder therefor, substantially as shown and described.
